[57] **CLAIM**

The ornamental design for a handle for hand tool, as shown and described.

DESCRIPTION

FIG. 1 is a top plan view of a handle for hand tool, showing my new design;

FIG. 2 is a left side elevational view thereof, the right side being a mirror image;

FIG. 3 is a bottom plan view thereof;

FIG. 4 is a left end elevational view thereof; and,

FIG. 5 is a right end elevational view.

The broken line showing of the wrench head is for illustrative purposes only and forms no part of the claimed design.
